MILTON F. WARD, OF EAST ST. LOUIS, ILLINOIS.

WATER-GAUGE FITTING.

Application filed May 5, 1924. Serial No. 711,088.

This invention relates to improvements in water gauge fittings, and consists in the novel construction hereinafter disclosed.

An object of the invention is to provide a fitting adapted to support a water glass, together with illuminating means so arranged that the reflection of the light from said illuminating means will make the water glass visible, with provision for guarding the water glass to prevent dispersion of the glass particles in the event the glass is broken.

Another object of the invention is to provide a water glass fitting equipped with illuminating means for illuminating high pressure marine or stationary service constructed from a unitary casting and designed for convenient mounting in the water line.

Additional advantages of the structure will appear from the following detailed description taken in connection with the accompanying drawing, in which

Fig. 1 is a plan view of the fitting.

Fig. 2 is a side elevation partially in section.

Fig. 3 is an elevation at right angles to Fig. 2.

In the embodiment of the invention illustrated in the drawing the fitting is shown as including a metallic frame substantially triangular in cross section and comprising panels 1 and 2 and a side wall 3, the upper and lower end of the fitting being closed by a top plate 4 and a bottom plate 5. The whole fitting thus described is preferably made from a unitary casting from which projects a casing 6 for the illuminating means. The panels 1 and 2 are in the form of an open frame having angular flanges 7 running longitudinally thereof and at the sides. The flanges 7 constitute retaining means for transparent panes 8, thereby providing window openings through which the water glass 9 supported within the fitting may be observed.

The angular arrangement of the panels 1 and 2 provides a structure so that natural light is admitted to the fitting, thereby equipping the fitting so that the gauge may be read either by natural or artificial light.

The water glass is in the form of a tube that is fitted between the plates 4 and 5. Stuffing boxes and pipe connections 10 are mounted on each of the end plates 4 and 5 in communication with the respective ends

of the water glass, thereby affording means for connecting the water glass with the pipe line. The wall 3 has a cut out portion or opening near the base of the fitting, said opening being closed by a screened closure 60 11 attached to the wall 3 adjacent to the edges of the opening by screws 12. This reticulated opening provides means of escape for the high pressure steam in event of breaking of the water glass. 65

The wall constituting the partition between the casing 6 and the interior of the fitting is provided with a longitudinal slot 13 in parallel alinement with the water glass supported within the fitting. The longitudinal slot constitutes the only opening between the casing and the interior of the fitting and is positioned so that the light from the illuminating element is projected through the slot against the water glass rendering the 70 water glass visible so as to determine the level of the water therein.

The casing 6 is shown as provided with a separate top plate 14 on the under face of which is mounted a socket 15 having an electric light bulb 16. On the upper face of the plate 14 is a socket 17 for receiving an electric wire conduit 18, the wire within which, it will be understood, connects into the socket 15. 80 85

It is obvious that the invention may be modified in certain particulars without departing from the spirit and scope thereof.

What we claim and desire to secure by Letters Patent is:—

1. A water gauge fitting comprising a water gauge guard having converging integrally united front walls adapted to removably support transparent windows, a metallic back wall, end plates integral with said walls, a water gauge supported between said end plates within the guard, a housing integrally formed with said back wall and having a longitudinal slit through the wall adjacent to the guard, a separate cover plate 90 for said housing, and an illuminating element removably supported by said cover plate within said housing. 95 100

2. A water gauge fitting comprising a water gauge guard having converging integrally united front walls adapted to removably support transparent windows, a metallic back wall, end plates, a water gauge supported between said end plates within the guard, a housing integrally formed with 105 110

- said back wall and having a longitudinal slit through the wall adjacent to the guard, said housing being provided with an open upper end for the insertion of an illuminating element, a separate cover plate for said housing, and an illuminating element removably supported by said cover plate within said housing.
3. A water gauge fitting comprising a water gauge guard having converging front walls adapted to removably support transparent windows, a metallic back wall, end plates, a water gauge supported between said end plates within the guard, a housing integrally formed with said back wall and having a longitudinal slit through the wall adjacent to the guard and provided with an open upper end for the insertion of an illuminating element, said housing extending downwardly from the upper part of said

- back wall to a point remote from the lower end, an illuminating element removably supported within said housing, and a screened opening disposed below said housing.
4. A water gauge fitting, comprising a frame triangular in cross section, transparent panels supported by two walls of said frame, an illuminating element casing supported by the other wall of said frame, there being a longitudinal slot between the casing and the frame and an opening in said other wall below said casing, a water glass supported within the frame in longitudinal alignment with said slot, and a screen covering said opening in said other wall below said casing.
